[57] CLAIM

The ornamental design for an animal hydrotherapy tank, substantially as shown and described.

DESCRIPTION

FIG. 1 is a perspective view of an animal hydrotherapy tank, showing our new design;

FIG. 2 is a side elevational view of the animal hydrotherapy tank shown in FIG. 1, the other side being identical thereto;

FIG. 3 is a bottom plan view of the animal hydrotherapy tank shown in FIG. 1;

FIG. 4 is a front elevational view of the animal hydrotherapy tank shown in FIG. 1, the rear being identical thereto; and

FIG. 5 is a top plan view of the animal hydrotherapy tank shown in FIG. 1.
